DESIGN.

E. W. DOUGHTY.

TEXTILE FABRIC,

APPLICATION FILED AUG. 14, 1917.

51,300.

Patented Sept. 25, 1917.

Inventor

Emma W. Doughty

By her attorney

Matthew Allen

UNITED STATES PATENT OFFICE.

EMMA W. DOUGHTY, OF CRESSKILL, NEW JERSEY, ASSIGNOR TO CHENEY BROTHERS,
OF SOUTH MANCHESTER, CONNECTICUT, A CORPORATION OF CONNECTICUT.

DESIGN FOR A TEXTILE FABRIC.

51,300.

Specification for Design.

Patented Sept. 25, 1917.

Application filed August 14, 1917. Serial No. 186,242. Term of patent 3½ years.

To all whom it may concern:

Be it known that I, EMMA W. DOUGHTY, a citizen of the United States, residing at Cresskill, Bergen county, New Jersey, have invented a new, original, and ornamental Design for Textile Fabrics, of which the following is a specification, reference being had to the accompanying drawing, forming a part thereof.

The figure is a plan view of a portion of a textile fabric, illustrating my new design.

I claim—

The ornamental design for a textile fabric as shown.

EMMA W. DOUGHTY.
